FIRE EXTINGUISHER

Carl A. Norgren, Denver, Colo.

Application October 26, 1931, Serial No. 571,137

10 Claims. (CL 169—31)

This invention relates to fire extinguishers of the type exemplified in the co-pending application for Patent Serial No. 509,166, filed January 16, 1931.

5 The distinguishing feature of this type of extinguisher resides in the provision of a container for a fire-extinguishing liquid, such as carbon tetrachloride, and in direct connection therewith a normally sealed capsule containing a pressure 10 gas and having an outlet closed by a seal which when punctured, admits the gas to the container. The container has a normally closed outlet through which the fire extinguishing liquid is forcibly ejected under pressure of the expanding 15 gases, and manually operated means are provided for puncturing the seal of the capsule when the device is put in operation. The present invention resides in improvements in details of construction and in the provision of improved 20 and newly devised parts all of which enhance the efficiency of the extinguisher and aid in maintaining it in a condition for instant use during an unlimited period of time, and under circumstances which frequently impair the oper- 25 ativeness of extinguishers of different types used heretofore.

The nature and construction of the improvements will be fully brought out in the following description and in the hereunto appended claims, 30 it being understood that while the novel features of the present invention have been shown in a practical form, variations in their form and construction may be resorted to within the scope of the invention.

35 In the accompanying drawing in the several views of which like parts are similarly designated,

Figure 1 represents a partially broken elevation of the improved extinguisher,

40 Figure 2, a sectional elevation of the upper end-portion of the same, drawn to an enlarged scale,

Figure 3, a section taken on the line 3—3, Figure 2, and

45 Figure 4, an enlarged sectional view of the strainer at the intake end of the siphon tube of the device.

50 Referring further to the drawing, the improved fire extinguisher comprises a cylindrical container 5 made of suitable pressure-resisting metal such as drawn steel, and having semi-spherical ends. The container may be copper-plated, interiorly, to resist corrosion and its exterior surface may be nickel plated or otherwise finished.

55 The cylinder is usually made in two parts lap-

ping end-portions of which are united by means of a carefully applied solder to provide a hermetically sealed joint. The container thus constructed is capable of withstanding unusually large pressures far exceeding the pressure of approximately 250 pounds to which the device is subjected in ordinary use.

5 The container has at its upper end, a central opening 6 in which fits an exteriorly flanged neck 7 for the support of a capsule-housing 8. 10

The flange 7a of the neck engages the inner surface of the container around the opening and the housing 8 has a corresponding shoulder 8a bearing upon the outer edge of the neck 7.

15 The capsule housing and the neck have, respectively, exterior and interior screw threads whereby the one may be screwed into the other, and a gasket 9 preferably made of copper, placed between the shoulder of the housing and the end of the neck, seals the joint between the parts. 20 The capsule-housing is of one-piece construction, it is exteriorly threaded at its upper open end for the application of a screw-cap 10, and it has at its lower end, within the container, a recess 12 to provide a seat for the slightly smaller neck 25 13a of the capsule shown at 13.

25 The body of the capsule occupies the housing and projects without the same into the screw-cap 10 and the contracted neck 13a of the capsule is hermetically closed at its end by a metallic 30 seal 14 so formed that it may be punctured under pressure to provide an outlet for the pressure fluid with which the capsule is filled at the factory. A sealing ring 15 made of soft leather 35 or other suitable material, is placed in the recess to support the capsule and to effect an air-tight seal when the capsule is pressed downwardly by rotation of the screw-cap. A small paper lining 16 is placed around the body of the capsule inside 40 the housing to prevent rattling of the capsule especially when the extinguisher is mounted in or transported by a moving vehicle. Supported upon the bottom of the recess 12 by means of a flange 17a is a sharp-pointed prong or needle 17 which extends through the sealing ring 15 and 45 which is adapted to puncture the seal of the capsule under pressure. The prong or needle has an axial bore for the passage of fluid discharged from the capsule into a valve chamber 18 at the extreme inner end of the housing 8, and thence through one or more apertures 19a in the wall of a screw-cap 19 that closes the valve-chamber, 50 into the container 5.

55 A spring-pressed disk-valve 20 provided with a seal of soft resilient material not affected by

the liquid in the container normally closes the opening between the valve-chamber and the recess, in which the prong is fitted. The valve provides an effectual seal against the loss of fluid 5 from the container by evaporation.

An apron 21 fastened to the neck 7 and projecting into the container, determines the level to which the container may be filled and thereby provides for an expansion-space above the liquid, 10 of sufficient size to insure in the operation of the device the instant and constant ejection of the fire extinguishing liquid in a steady stream by pressure of the expanding gases discharged from the punctured capsule. 15

15 The outlet of the container is provided with a jet 22 at the upper portion of the same. The jet or nozzle is screwed into a shouldered plug 23 sealed in an opening of the container, and its narrow bore is alined with a bore of the plug, 20 into which the liquid contents of the container are ejected by means of a siphon-tube 24.

The siphon-tube extends in substantially parallel relation to the axis of the container, to a point adjacent the lower end of the same, 25 and terminates in a strainer-block 25 held against the side of the container by means of a tensioned copper-coated steel spring 26.

The spring is placed transversely of the container and it braces the strainer-block so as to hold it firmly in contact with the wall thereof. 30 The block has an open recess 26a provided with apertures 26c for the entrance of the liquid and in the recess is a bronze strainer 27 over an opening of the block in which the end of the siphon-tube is fitted. The strainer-fixture not only prevents the entrance of dirt particles which possibly might obstruct the free flow of liquid through the tube and the jet, but also holds the lower end of the siphon-tube in fixed 35 position. 40

The end-portions 24a and 24c of the siphon-tube extend at an angle to the body portion of the same and in diverging relation to each other and the bore of the jet connecting with the upper 45 end-portion of the tube, is at an angle of approximately forty-five degrees to the axis of the container, all of which aids in effecting a forceful ejection of the liquid unhampered by unwarranted friction with the parts through which it passes, and makes it possible to entirely drain 50 the container of all of its liquid contents.

In this connection, it is to be understood that in the use of the extinguisher, the container is held with its top above the horizontal at any 55 desired angle. The jet or nozzle at the upper end of the container is normally closed by a seal of resilient material fitted and secured within a small cap 28 which is swiveled in an opening of a flat sealing spring 29. The spring is at one 60 end hingedly connected with a clevis 30 clamped around the exterior portion of the plug 23 and a bent tip 29a at its opposite end bears against the screw-cap 10 at the lower edge thereof.

The cap has immediately above its said edge a 65 circumferential groove 10a provided with a notch 10c to release the tip from the edge of the cap when the latter is screwed upon the capsule housing.

The spring 29 presses the seal-member 28 70 firmly against the end of the jet and at the same time presses upwardly against the cap to effect a fluid tight contact between its screw-threads and those of the capsule-housing.

When the parts are in their normal positions 75 ready for use, the screw-cap is held against ro-

tation by means of a small wire seal 31 passing through openings in the cap and the shoulder of the capsule-housing.

This seal is easily broken and its principal object is to provide for inspectors visual evidence that the extinguisher is in its original operative condition and has not been tampered with.

In practise, the container is filled with a fire-extinguishing liquid, preferably carbon tetrachloride, to the level determined by the apron 10 21 and a capsule filled with a pressure gas, preferably liquefied carbon dioxide, is placed in the capsule-chamber and pressed against the sealing-ring 15 by means of the screw-cap 10. The tip 29a of the sealing spring is engaged by the end 15 of the screw-cap and the latter is sealed in place by the wire seal 31. It is an important feature of the invention that under normal conditions the liquid in the container is not under pressure, the pressure required for its expulsion being provided only when by puncturing the seal of the capsule, the pressure gas contained therein is liberated to enter the expansion space above the liquid in the container. The fire-extinguishing liquid is ejected from the container only by the 20 expansive force of the liberated gases. No chemicals or other means for generating gases are employed.

It is to be noted that the improved extinguisher has but three parts that may open to the atmosphere and that all of these parts are hermetically sealed against loss of fluid by evaporation or leakage. Withdrawal of any part of the fire-extinguishing liquid or removal of the capsule, or unwarranted rotation of the screw-cap without detection are prevented by the wire seal and corrosion of the jet is prevented by the spring-pressed seal 28 which hermetically closes and covers the same as long as the screw-cap is in its normal position as shown in Figure 1. In case 40 of fire, the operator grasps the container in one hand and directs the jet-opening toward the blaze.

With the other hand, the operator advances the screw-cap upon the capsule housing with the 45 result that the seal 31 is broken, the sealing spring 29 is released and the closure of the capsule is broken with the result that the pressure gas is released into the expansion space above the liquid-level of the container. The high pressure of the 50 expanding gas upon the liquid causes the latter to be forcibly ejected through the now open jet. The ejected stream breaks up in the form of a spray at a comparatively short distance from the extinguisher and the spray being vaporized by 55 the heat of the fire, forms a gas which extinguishes the same.

Owing to peculiar construction and position of the siphon tube, the entire contents of the container are thus discharged within the time required by the underwriters.

When the seal of the capsule is pressed into contact with the prong which punctures the same, the neck of the capsule is at the same time driven onto the sealing ring which by its consequent 65 compression prevents the gas from escaping to the atmosphere.

The liquid is discharged through the jet at high velocity in a continuous steady stream which is accurately directed to the fire, and if at any 70 time during the operation, it is desired to discontinue the issuance of the fire extinguishing liquid, the jet opening may be instantly closed by placing the index finger of the hand in which the container is held, over the opening.

The parts of the jet assembly may be cadmium plated to prevent possible corrosion by acid fumes, salt air or other causes, and inasmuch as the ejection of the fire-extinguishing liquid through the jet is continued until all the contents of the container have been discharged, the possibility of keeping a partially emptied extinguisher for future use, is eliminated and the device must be restored to its original condition by the provision of a fresh quantity of carbon tetrachloride, and a new charged capsule, before it may be used again.

What I claim and desire to secure by Letters Patent is:

1. A fire extinguisher comprising a container having an opening at an end thereof, a neck projecting inwardly from the opening, a capsule housing held by the neck, to project at opposite sides of the opening, and having at its inner end a recess and a valve chamber connected therewith by a passage, a bored puncturing prong in the passage, a spring-pressed valve in the valve chamber, a screw-cap upon the lower end of the capsule housing having an egress-aperture extending laterally with respect to the axis of the housing, in connection with the valve-chamber, a resilient gasket in the recess, a sealed capsule in the housing resting upon the gasket and extending beyond the outer portion of the housing, and a screw-cap upon said outer portion of the housing, engaging the capsule.

2. A fire extinguisher comprising a container for a fire extinguishing liquid, a capsule for a pressure gas, housed at an end of the container, and having a sealed outlet within the same, means for breaking the seal, to admit the pressure gas to the container, by movement of the capsule, a device to effect said movement of the capsule from without the container, a jet for the forcible discharge of the liquid from the container under fluid-pressure, a closure for the jet, and spring-means pressing upon the closure and the said device to effect their fluid-tight engagement with the parts with which they are associated, the said spring-means and the device being cooperatively associated to jointly effect a separation of the closure from the jet-opening in the operation of the extinguisher.

3. A fire extinguisher comprising a container for a fire extinguishing liquid, a capsule for a pressure gas, housed at an end of the container, and having a sealed outlet within the same, means for breaking the seal, to admit the pressure gas to the container, by movement of the capsule, a screw cap to effect said movement of the capsule from without the container, a jet for forcible discharge of the liquid from the container under fluid-pressure, a closure for the jet and spring means holding the closure in place by engagement with the screw-cap, said spring means and the screw-cap having means for releasing the spring from engagement with the screw cap upon rotary movement thereof, thereby releasing said closure from said jet.

4. A fire extinguisher comprising a container for a fire extinguishing liquid, a capsule for a pressure gas, housed at an end of the container, and having a sealed outlet within the same, means for breaking the seal, to admit the pressure gas to the container, by movement of the capsule, a screw-cap to effect said movement of the capsule from without the container, a jet for forcible discharge of the liquid from the container under fluid-pressure, a closure for the jet and spring means holding the closure in place by engagement

with the screw-cap, the screw-cap having a notch to release the spring means, during a rotary movement of the cap.

5. A fire extinguisher comprising a container for a fire extinguishing liquid, a capsule for a pressure gas, housed at an end of the container, and having a sealed outlet within the same, means for breaking the seal, to admit the pressure gas to the container, by movement of the capsule, a screw-cap to effect said movement of the capsule from without the container, a jet for forcible discharge of the liquid from the container under fluid-pressure, a closure for the jet, a spring holding the closure in place, hinged at one end and having at its opposite end, a tip engaging the screw-cap, the latter having a notch to release the tip of the spring during rotary movement of the cap.

6. In a fire extinguisher, a container for fire-extinguishing liquid, having at one end a normally closed outlet, mechanism to subject the liquid in the container to fluid-pressure, for its forcible ejection through the outlet, a tube extending from the outlet, lengthwise of the container and having an intake portion bent toward the wall of the container at the opposite end of the same, a strainer-element against the wall, in connection with said intake portion, and spring-means for holding the element in place.

7. In a fire extinguisher, a container for fire-extinguishing liquid, having at one end a normally closed outlet, mechanism to subject the liquid in the container to fluid-pressure, for its forcible ejection through the outlet, a tube extending from the outlet, lengthwise of the container and having an intake portion bent toward the wall of the container at the opposite end of the same, a strainer-element against the wall, in connection with said intake portion, and a spring transverse of the container, bracing the element in place.

8. In a fire extinguisher, a container having a discharge nozzle, a casing having a rupturable wall portion within the container, manually operable means for opening communication between the container and the casing through said rupturable wall portion, and a spring plate releasably engaged with the manually operable means and with the nozzle to effect closure of the same, said spring plate and said manually operable means being arranged to effect release of the spring plate from said manually operable means and from said nozzle upon opening of the casing by movement of said manually operable means.

9. In a fire extinguisher, a closed container having a discharge nozzle, a closed casing having a rupturable wall portion within the container, manually-operable means acting upon said wall portion for opening communication between the chambers of the container and casing, and a spring-plate releasably engaged with the manually-operable means and closing the nozzle and released by movement of said means.

10. In a fire extinguisher, a closed container having a discharge nozzle, a closed casing having a rupturable wall portion within the container, manually-operable means acting upon said wall portion for opening communication between the chambers of the container and casing, and a bowed spring-plate slidably but detachably engaged with the manually-operable means and detachably engaged with and closing the nozzle and released by movement of said means.
